UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,570, dated August 21, 1894.

Application filed July 28, 1894. Serial No. 518,888. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of panels formed by double lines arranged in a diagonal 10 manner over the surface of the paper with a small rosette ornament at the intersecting points of said lines and a lotus flower-shaped ornament in the center of each panel as represented in the accompanying drawing. The 15 border or upper portion of the design is also

formed of double lines in the form of panels with small rosettes at intersecting points and lotus flower-shaped ornaments in the center of said panels as shown in the drawing.

What I claim is—

1. The design for wall paper herein shown and described.
2. In the design for wall paper, the border herein shown and described.

Witness my hand this 26th day of July, 25 1894.

CHARLES BOOZE.
